ARTHUR J. HODGE AND HENRY B. RUGGLES, OF PASADENA, CALIFORNIA, ASSIGNEES
TO THE AMERICAN PRODUCTS COMPANY, OF ST. LOUIS, MISSOURI.

HEAD FOR BARRELS AND THE LIKE.

1,276,362.

Specification of Letters Patent. Patented Aug. 20, 1918.

Application filed April 14, 1915. Serial No. 21,432.

To all whom it may concern:

Be it known that we, ARTHUR J. HODGE and HENRY B. RUGGLES, citizens of the United States of America, residing at Pasadena, in the county of Los Angeles and State of California, have invented certain new and useful Improvements in Heads for Barrels and the like, of which the following is a specification.

10 This invention has relation to certain new and useful improvements in heads for barrels and the like and has for its primary object, the provision of a form of removable head which may be readily placed in position and secured against movement and sealed to prevent unauthorized parties from gaining access to the contents of the barrel.

15 The invention has for another object, the provision of a head of this character including a pair of radially split disks of concavo-convex form and means for retaining the same in a flattened position with their circular edges engaged in the croze of the barrel to prevent movement or withdrawal of the 20 head.

25 The invention has for a further object to provide novel supporting and securing means for the disks comprising the head and a simple and improved form of seal which 30 not only serves to prevent withdrawal of the head without destruction of the seal but which also serves to retain the disks in flattened position with their circular edges pressing against the vertical wall of the 35 croze.

40 The invention has for a still further object, the provision of a novel form of staple carried by a transverse supporting bar for the head and projecting through the central 45 inforced openings of the disks of said head to receive the seal after the central portions of said disks have been pressed downwardly to flatten out said disks with the lower disk pressing the upper face of the transverse 50 supporting bar.

With these and other objects in view, the invention consists in the novel construction

and combination of parts as will be more in detail described, and the asserted novelty specifically pointed out in the claims.

50

In the accompanying drawings which clearly and fully illustrate the invention:—

Figure 1 is a top plan view of the upper portion of a barrel or keg with our improved form of head secured therein and sealed in 55 position;

Fig. 2 is a transverse vertical section, substantially on the plane of line 2—2 of Fig. 1;

Fig. 3 is a view similar to Fig. 1, showing the position of the disks of the head after 60 removal of the seal or before the seal has been applied;

Fig. 4 is a transverse vertical section on the plane of line 4—4 of Fig. 3; and

Fig. 5 is a detail perspective view of the 65 staple, removed.

Referring more particularly to the drawings in which similar reference characters designate corresponding parts throughout the several views, 1 designates the upper 70 portion of a barrel or the like provided with an ordinary form of croze 2, thereby forming the lower shoulder 3 and the upper shoulder 4 for the lower and upper horizontal walls of the croze 2. Within the barrel 1 is positioned a transverse horizontal supporting bar 5, which has its opposite ends resting in suitable recesses 6' located at diametrically opposite points of the barrel so that when the bar 5 is in position, the upper 75 face of the same is substantially flush with the face of the shoulder 3, the purpose of which will presently appear.

The horizontal or transverse supporting bar 5 has a central opening 6 through which 80 projects upwardly the body of the staple 7. Beneath the horizontal transverse supporting bar 5, the opposite legs of the staple 7 are extended outwardly in a horizontal direction and longitudinally of the bar 5, as 85 shown at 8, then bent back upon themselves as shown at 9. Each leg, after being bent back is extended and wrapped around the portion of the staple from which the oppo-

site leg is first extended, as shown at 10 and bent at about a right angle to form an arm 11 extended transversely of the bar 5 and terminating in an upwardly directed prong 12 to be forced into the bar 5 to secure the staple 7 in position. It will be evident that by bending the legs of the staple 7 in this manner and wrapping them around the main portion or body of said staple 7, the same 10 will be strengthened and prevented from spreading or turning after the prongs have been forced into the bar 5.

The head comprises a pair of disks numbered 13 and 17 and formed preferably of compressed pulp or fiber, but it will be understood that these disks may be formed of any suitable material. The disk 13 is of concavo-convex form and has a radially extending slit therein, which is numbered 14 and is extended inwardly from its outer or circular edge to the central opening 15 of said disk 13, within which central opening 15 is secured the reinforcing eyelet 16. The eyelet 16 also serves to receive the staple 7 20 when the disk 13 is placed in position in the receptacle, as clearly shown in Figs. 2 and 4 of the drawings.

The disk 13 is shown as serving as the inner disk or first disk and after the same has 30 been placed in position, the second disk or outer disk 17 is placed upon the same, as shown in Fig. 4. The second disk or outer disk 17 is also of concavo-convex form and has a radially extending slit 18, which extends from the outer or circular edge thereof inwardly to the central opening 19 of said disk 17, within which is secured the reinforcing and staple receiving eyelet 20 similar to the eyelet 16 and directly above the same 40 when both of the disks 13 and 17 are in position as shown in Figs. 2 and 4.

The disks 13 and 17 are placed in position so that the slit 14 of the disk 13 extends longitudinally above the bar 5 and toward one 45 end thereof while the slit 18 of the disk 17 extends in the opposite direction and is therefore directly above a solid portion of the disk 13 over the opposite end of the bar 5. It will be noted, by referring to Fig. 4 of 50 the drawings, that the disks 13 and 17 are of about the same diameter and equally spaced from the vertical wall of the croze 2.

To secure the inner disk 13 and the outer disk 17 in position and seal the head or cover, the central portions of the disks 13 and 17 are pressed downwardly by applying the proper pressure to the outer face of the outer disk 17 until the disks 13 and 17 are flattened out sufficiently to press the outer 55 or circular edges of said disks 13 and 17 tightly against the vertical wall of the croze 2, as clearly shown in Fig. 2 of the drawings. The protecting washer 21 of metal or other suitable material is then placed over

the projecting outer end of the staple 7 and the straight leg 22 of the substantially elliptical wire seal is threaded through the end of the staple 7. The leg 22 is moved through the staple 7 until the latter passes beneath the inwardly offset stop portion 23 of the opposite or irregular leg and said staple reaches a point opposite the outwardly offset portion 24 of the last mentioned leg of said seal. The seal proper 26 is formed of lead or some other suitable soft material 75 and is threaded upon the turned back free end 25 of the irregular leg of said seal and is moved along the irregular leg toward the staple 7 until it is engaged over the free end of the straight leg 22 and closes the 80 space between said free end and the bent back end 25 of the second mentioned leg. When the seal proper 26 is in this position, it covers the teeth 27 cut in one face of the straight leg 22 adjacent the free end thereof 85 and in an opposite portion of the second mentioned or irregular leg, and said seal proper 26 is ready to be pressed together by engagement of pliers or any other suitable tool with opposite sides of said seal proper 90 26, to clamp the latter in this position and cause the teeth 27 to bite into said seal proper and thereby prevent unauthorized parties from removing the head without first 95 destroying the seal proper 26. It will be evident that when the seal proper 26 is moved to position to be clamped or squeezed upon the teeth 27 and thereby seal the head or cover in position, the opposite legs of the wire seal are drawn toward one another and the inwardly offset stop portion 23 of the irregular leg will prevent movement of the seal in one direction through the staple 7. The opposite end of the seal, owing to the 100 small space between the legs thereof, will prevent the seal from moving in the opposite direction. It will therefore be impossible to move the wire seal in either direction through the staple 7 after the seal proper 26 has been compressed. 105

The last mentioned end of the seal where the straight and irregular legs connect at their inner ends is bent at about a right-angle to form the hook 28 which may be employed for the purpose of removing the 115 disks 17 and 13 of the head after destruction of the seal proper 26 and removal of the wire seal from the staple 7. It will be readily understood that, as soon as the wire seal is removed from the staple 7, the disks 120 17 and 13 will spring to their normal or original positions, as shown in Fig. 4 and it will simply be necessary to engage the hook 28 through the eyelets 20 and 16 of the disks 125 17 and 13 respectively to withdraw said disks from the receptacle and it will be evident that the use of the hook 28 will be desirable owing to the fact that it will be

practically impossible to engage a finger or a tool between the edges of the disks 17 and 13 and the receptacle to remove said disks.

When placing the head in position, the 5 disks 13 and 17 should be inserted one at a time as it is necessary to grasp the disk at opposite sides of the slit thereof and overlap the slit portions of the disk and hold the same in this position until the disk is 10 inserted, when it may be released and allowed to spring to normal position, as clearly shown in Fig. 3 with the edges of the slit close together and practically parallel. When the central portions of the disks 13 15 and 17 are pressed downwardly and the disks thereby flattened out, however, the edges of the slits thereof will separate as clearly shown in Fig. 1 of the drawings, thereby permitting the outer circular edges 20 of said disks 13 and 17 to move outwardly and press against the vertical wall of the croze 2.

It will be understood that while we have shown and described the use of two concavo- 25 convex disks with the convex face of both positioned outwardly, any suitable number of disks may be employed, as desired and it will further be understood that many changes in the form, proportion and minor 30 details of the construction which fall within the scope of the appended claims, may be resorted to without departing from the spirit and scope of the invention or sacrificing any of the advantages of the same.

35 What is claimed is:—

1. A head composed of a pair of radially slit disks, the slit of one disk being opposed to the solid part of the other for completing the closure, a supporting member for 40 said disks, said disks being adapted to be flattened upon said supporting member, and means for retaining said disks in flattened position with their edges expanded.

2. A head comprising a pair of disks resting one upon the other and having oppositely extending radial slits whereby a complete closure may be obtained, a transverse supporting member for said disks, the central portions of said disks being spaced 50 above said supporting member normally, a staple member carried by said supporting member and projecting through said disks, and means threaded through and locked upon said staple member outwardly of said 55 disks to retain the latter in flattened position upon said supporting member with their edges expanded.

60 3. A head comprising a pair of radially slit concavo-convex disks, the slit of each disk being extended in a direction opposite to the slit of the remaining disk, a supporting bar beneath said disks, said disks being positioned with their slit portions directly above said supporting bar, the center of said

disks being normally spaced from and 65 adapted to be pressed toward said supporting bar to flatten out said disks and force the edges thereof outwardly, and means for sealing said disks in flattened position.

4. A head comprising a pair of radially 70 slit expanding disks, sleeves at the center of the disks, the central portions of said disks being raised and being adapted to yield downwardly for expanding the edges of said disks, and means for retaining said disks 75 against movement and sealing the head in expanded position.

5. The combination with a receptacle; of 80 a supporting bar within the same, a radially slit expanded head above said supporting bar and in binding engagement with the interior of said receptacle, and means rigid on said supporting bar and projecting through said head to prevent movement of 85 said head.

6. The combination with a receptacle; of 90 a head supporting bar positioned therein, a pair of radially split head forming disks resting upon one another and upon said supporting bar, strengthening rings at the center of each disk, said disks having their central portions pressed toward said supporting bar and their circular edges in binding engagement with the interior of said receptacle, and means for sealing said head in 95 position and preventing movement of the same.

7. The combination with a receptacle having a croze formed therein; of a stationary transverse supporting bar below said croze 100 and having its upper face flush with the lower shoulder of said croze, a head composed of a pair of disks and resting upon the ends of said supporting bar, the centers of said disks being spaced above said bar 105 normally, said disks having registering central openings, a staple projecting through said supporting bar and into the central openings of said disks, the lower ends of said staple being bent around one another 110 and forced into the lower face of said supporting bar to prevent spreading or movement of said staple, said disks being adapted to be pressed downwardly and expanded to force the edges thereof into binding engagement with said croze, and means for engagement through the projecting end of said staple to seal the head in position and prevent withdrawal or movement of the same. 115

8. The combination with a receptacle having a croze and a transverse supporting bar therein; of an upwardly projecting staple carried by said bar, a centrally apertured head resting upon the ends of said bar, said head being adapted to be pressed toward 125 said supporting bar to permit the staple to project through said head and to force the outer edge of said head into binding engage-

ment with the wall of said croze, a wire seal for removable engagement through the projected end of said staple to retain said head in flattened and expanded position, said wire seal having one end bent to form a hook for withdrawing said head from within the receptacle after removal of said wire seal from said staple, and a seal locking member upon said wire seal and adapted to be moved 10 to operative position to tighten said wire

seal and compressed to prevent withdrawal of said wire seal.

In testimony whereof we affix our signatures in presence of two witnesses.

ARTHUR J. HODGE.
HENRY B. RUGGLES.
